UNITED STATES PATENT OFFICE.

CARL E. EKLIND, OF BERWYN, ILLINOIS, ASSIGNOR TO CAMEL COMPANY, OF CHICAGO, ILLINOIS, A CORPORATION OF ILLINOIS.

CAR-DOOR GUARD STRIP.

Application filed September 13, 1924. Serial No. 737,522.

To all whom it may concern:

Be it known that I, CARL E. EKLIND, a citizen of the United States, residing at Berwyn, in the county of Cook and State of Illinois, have invented certain new and useful Improvements in Car-Door Guard Strips, of which the following is a specification.

This invention relates to a strip, in the nature of a curb or bar applied to a freight car or in other similar situations, in position to be engaged by a co-acting strip or bar carried upon the rear end of the car door, in order to effect a weather-tight closure of the door-way. Guard strips of this kind have heretofore been shaped to provide an eddy pocket, a striking salient and a resilient sealing lip, but these elements were not related in a manner to develop the best results as to efficiency and durability in service; moreover their relative positions in the organization of the strip were such as to develop a form that was relatively expensive to produce.

The object of the present invention is to provide a weatherproofing guard strip for car doors or the like which will be more efficient in service and more durable in use than guard strips as heretofore constructed and which may be given its characteristic shape in the rolling mill so that the strip may be provided by merely cutting off a suitable length of stock material. Accordingly, the invention consists in forming a guard strip of the kind stated, with an attaching base extending outward from the car body (regarded in its relation to the door post) and providing one wall of the eddy pocket, and an offset web extending rearwardly from said attaching base a distance sufficient to form the second wall of the eddy pocket, a deflected portion extending from the rear line of the web portion, in a direction that is inward and approximately parallel with the attaching base, forming a third side of the eddy pocket and terminating in a striking salient, and a resilient sealing lip extending rearwardly from the salient but inclined outwardly to receive the co-acting weather bar carried by the door; the effect of this relationship of the parts being to present a resilient end toward the door member, to arrest the forward portion of the door strip against the relatively rigid salient, and to produce a

more efficient eddy pocket, while, as already stated, affording a shape of bar that can be produced by rolling.

In the accompanying drawing,

Figure 1 is a view of a fragment of a freight car doorway and door in horizontal section shewing, in transverse section, a strip constituting one embodiment of the present invention.

Figures 2, 3 and 4 are perspective views of fragments of guard strips embodying the invention, slightly different in form, that of Figure 4 corresponding substantially to the form shown in Figure 1.

1 represents a portion of the side construction of a freight car body, 2 the post which defines the rear side of the doorway thereof, 3 the Z-bar commonly used as a reinforcing element for the door post, as well as a fac-
ing for the same, 4 a portion of the door, and 5 the weather strip or bar of known construction, commonly used on the rear margin of the door. In order to make a weather-tight connection at the rear end of the door, it is customary to mount upon the door post 2, through the medium of the Z-bar 3, or other available structural mem-
bers, a guard strip 6 that will co-act with the weather bar 5 so long as the door is in closed position. As in known constructions employing an attaching base 7 upon the rear outer face of the door post 2 or Z-bar 3, and therefore extending outwardly from the car body, and forming one wall of an eddy pocket, the present invention employs a rear-
wardly extending portion 8 forming a second wall of the eddy pocket, but instead of continuing this portion to the extreme rear end to form a striking salient, as in known constructions, the present invention reduces the portion 8 to a mere offsetting web for a deflected portion 9 extending in-
wardly from the rear line of the offsetting web, and substantially parallel with attach-
ing base 7, so that it forms the third side of the eddy pocket, and this deflected portion 9 terminates in a relatively rigid salient 10 which constitutes the striking point of the co-acting weather bar 5 of the door, at the end of the closing movement, and the guard strip terminates, according to the present in-
vention, in a resilient sealing lip 11 extending rearwardly from the salient 10 rather than forwardly as in prior practice, but in-
clined outwardly so that the flange 12 of the

weather strip 5 will ride upon it. In other words, the weather strip carried by the outer face encounters a resilient portion of the stationary guard strip which ultimately becomes its sealing lip, and brings up against the relatively more rigid striking salient at the end of its movement, and the eddy pocket 13 has its third side directed substantially transversely to the joint between 10 the two members.

While the sealing lip 11 preferably terminates in a bead 14 as shown in Figures 1 and 4, such bead may be omitted and the sealing lip given the form 11^a, Figure 3, or 11^b, 15 Figure 2; and while the deflected portion constituting the third wall of the eddy pocket is preferably given the direction shown at 9 in Figures 1 and 4, and also at 9^a in Figure 3, it may be disposed at a greater 20 angle, as shown at 9^b in Figure 2; moreover the resilient lip 11 may be relatively flatter than is shown in Figures 1, 3 and 4, for instance as shown at 11^b in Figure 2.

An important feature in the preferred 25 embodiment of the present invention consists in having the sealing lip terminate substantially in the plane of the outer face of the offsetting web so that it will constitute a support for the lip in the rolling of the 30 section which constitutes the strip; this feature of the invention being better realized when the sealing lip terminates in a bead that is thus located, and especially if the bead be deflected outwardly from the sealing 35 lip, as by giving the outer portion of the sealing lip a roll or curvature; because in this way the bead by occupying the opposed grooves in the rolls, that form it, will be held against deflection under the pressure 40 which is imposed upon it in the forming operation. This particular form of lip, and especially when beaded as described, also functions better in serving the purposes for which it is intended.

45 I claim:

1. A guard strip for freight car doors, comprising in one rolled metal structure, an attaching base, an offsetting web extending rearwardly from said attaching base and providing a wall of an eddy pocket, a deflected portion extending inwardly from the rear line of said web, terminating in a striking salient and providing another wall of the eddy pocket, and a sealing lip extending 50 rearwardly but inclined outwardly from said salient, in position to receive a co-acting member on a door.

2. A guard strip for freight car doors 60 comprising in one rolled metal structure, an outwardly extending attaching base, constituting one wall of an eddy pocket, an offsetting web extending rearwardly from the outer line of said attaching base, and providing a second wall of the eddy pocket, a deflected portion extending inwardly from

the rear line of said web, terminating in a striking salient and constituting a third wall of said eddy pocket, and a sealing lip extending rearwardly but inclined outwardly from said salient, in position to receive a co-acting weathering member on a door. 70

3. A guard strip for freight car doors comprising, in one rolled metal structure, a plate-like attaching base adapted to lie in a plane transverse to the plane of door movement and constituting one wall of an eddy pocket, an offsetting flange extending in the direction of door movement, rearwardly from said attaching base constituting the second wall of an eddy pocket, an offsetting portion extending approximately parallel to the attaching base, from the rear line of said offsetting flange, constituting the third wall of the eddy pocket and terminating in a striking salient, and a member extending rearwardly from said salient but inclined outwardly toward the door, terminating in a free rear edge and constituting a resilient sealing lip adapted to cooperate with a weatherproofing member carried by the door. 90

4. A guard strip for freight car doors comprising in one rolled metal structure, an attaching base, an offsetting web extending rearwardly from said attaching base, having its outer face in a plane substantially perpendicular to the attaching base, and providing a wall of an eddy pocket on the inside, a deflected portion extending inwardly from the rear line of said web, terminating in a striking salient and providing another wall of the eddy pocket, and a sealing lip extending rearwardly but inclined outwardly from said salient, in position to receive a co-acting member on a door; said sealing lip terminating with its rear outer edge in the plane of the outer face of the offsetting web and providing a support for the sealing lip under the forming rolls. 100

5. A guard strip for freight car doors comprising in one rolled metal structure, an attaching base adapted to be applied to a surface perpendicular to the side of a car and constituting by its exposed surface, one wall of an eddy pocket, an offsetting web extending from the outer limit of said attaching base and formed with an outer face in a plane substantially perpendicular to the plane of the attaching base and with its inner surface forming a second wall of the eddy pocket, a deflected portion extending 115 from the offsetting web, in a direction substantially parallel to the attaching base, forming a third wall of the eddy pocket and terminating in a striking salient, and a sealing lip extending from said salient in an inclined direction outwardly and away from the attaching base, and having at its free edge a bead which terminates substantially 120 in the plane of the outer face of the offsetting web. 130

6. A guard strip for freight car doors comprising in one rolled metal structure, a plate-like attaching base adapted to be attached to a surface transverse to the side 5 of a car, an offsetting web extending from the outer limit of said attaching base, formed with an outer face substantially perpendicular to the attaching base and forming by its inner face, a wall of an eddy pocket, a deflected portion extending from the limit of said web remote from the attaching base, inwardly in a plane approximately parallel with the attaching base, forming another wall of the eddy pocket, 10 and terminating in a striking salient, and a sealing lip inclined in a direction outwardly from the salient and away from the attaching base, and formed at its free edge with an outwardly deflected bead that terminates in the plane of the outer face of 15 the offsetting web.
7. A freight car including a door frame and a sliding door, said door frame having rigidly mounted thereon a vertically disposed guard strip, said guard strip comprising a rolled metal structure having a 20 flat attaching portion, a rearwardly presented portion contiguous to one edge of said attaching portion, an inwardly presented portion contiguous to said rearwardly presented portion, said three portions forming three walls of an eddy pocket, said inwardly presented portion terminating in a striking salient, and a resilient sealing lip contiguous to said inwardly extending portion, said sealing lip being deflected outwardly, said sliding door being provided with a weather bar having a forwardly presented salient adapted to have sealing engagement with said sealing lip, said weather 25 bar and guard strip being so positioned relative to one another that in moving to closed position said salient of said weather bar encounters a relatively resilient portion of said guard strip, which ultimately becomes 30 its sealing lip and brings up against the relatively rigid striking salient at the end of its movement.
8. A freight car including a door frame and a sliding door, said door frame having rigidly mounted thereon a vertically disposed guard strip, said guard strip comprising a rolled metal structure having a 35 flat attaching portion, a rearwardly presented portion contiguous to one edge of said attaching portion, an inwardly presented portion contiguous to said rearwardly presented portion, said three portions forming three walls of an eddy pocket, said inwardly presented portion terminating in a striking salient, and a resilient sealing lip contiguous to said inwardly extending portion, said sealing lip being deflected outwardly, said sliding door being provided with a weather bar having a forwardly presented salient adapted to have sealing engagement with said sealing lip, said weather 40 bar and guard strip being so positioned relative to one another that in moving to closed position said salient of said weather bar encounters a relatively resilient portion of said guard strip, which ultimately becomes 45 its sealing lip and brings up against the relatively rigid striking salient at the end of its movement.

Signed at Chicago, Illinois, this 30th day of August, 1924.

CARL E. EKLIND.
